UNITED STATES PATENT OFFICE.

NATHANIEL LOMBARD, OF WINTHROP, MASSACHUSETTS.

MACHINE FOR CUTTING CHIPS FOR WOOD-PULP.

989,271.

Specification of Letters Patent. Patented Apr. 11, 1911.

Application filed May 24, 1910. Serial No. 563,449.

To all whom it may concern:

Be it known that I, NATHANIEL LOMBARD, a citizen of the United States of America, and a resident of Winthrop, in the county of 5 Suffolk and State of Massachusetts, have invented certain new and useful Improvements in Machines for Cutting Chips for Wood-Pulp, of which the following is a specification.

10 In the manufacture of wood pulp the usual practice is to cut logs in proper lengths and put them into a fan-like hopper in which is mounted a plurality of small steel knives revolving at a high rate of speed. These 15 knives quickly separate the logs into small chips which are carried away by means of a fan or other suction device to the digester where they are chemically treated to reduce the mass to pulp. This operation usually 20 makes the chips of all lengths, some of which are very short and have no binding effect when formed into pulp, while the knives break off small pieces of wood and knots which have to be separated from the 25 mass of chips prior to their entering the digester as they will not be properly acted upon by the chemicals to produce a suitable quality of pulp.

It has been found in practice that a very 30 large proportion of pulp wood is wasted in this manner and the object of the present invention is to overcome this objection and utilize all of the wood and reduce the waste material to a minimum.

35 A further object of the invention is to cut the chips into lengths substantially the same so that when acted upon by the chemicals to produce a pulpy mass, the lengths of the fiber being of substantially the same 40 length and uniform will have a binding effect that produces a very superior grade of paper of exceeding toughness.

To accomplish these objects the pulp wood is cut in the usual lengths and fed into a 45 hopper smaller at the top than at the bottom, the bottom of the hopper being above a revolute member having a plurality of chambers therein extending to the periphery of this revolute member.

50 At the mouth of each chamber is secured a cutter blade, the cutting edge of which is slightly beyond the periphery of the revolute member, this cutting edge extending transversely of the revolute member and 55 parallel to the grain of the wood in the hopper. Each cutter blade is provided with

a plurality of equally spaced slots in each of which is a knife the cutting edge of which extends beyond the periphery of the revolute member a distance equal to the distance 60 of the cutting edge of the cutter blade beyond said periphery so that as the revolute member revolves these knives will cut incisions through the grain of the wood upon the periphery of the logs and the cutting edge of the succeeding cutter blade will 65 cut from the logs chips of equal length. By cutting the incisions into the surface of the logs and then chipping off from the surface of the logs by means of the cutter blade 70 portions thus separated into equal lengths a superior pulp is secured which produces a high grade of this class of paper.

The invention consists in certain novel features of construction and arrangement of 75 parts which will be readily understood by reference to the description of the drawings and to the claims hereinafter given.

Of the drawings: Figure 1 represents an elevation of an apparatus embodying the 80 features of the present invention. Fig. 2 represents a transverse section of the same, the cutting plane being on line 2—2 on Fig. 1. Fig. 3 represents a sectional detail showing a portion of the revolute member, a 85 cutter blade thereon, and one of the knives for cutting the incisions into the surface of the logs. Fig. 4 represents a horizontal section of the same, the cutting plane being on line 4—4 on Fig. 2, and Fig. 5 represents a 90 plan of a portion of the revolute member showing the cutter blade and the plurality of knives in its rear edge.

Similar characters designate like parts throughout the several figures of the drawings. 95

In the drawings, 10 and 11 represent two side frames connected together by the end frames 12 and 13. These side frames 10 and 11 have bearings 14 in which is mounted 100 a revolute shaft 15, to one end of which is secured a driving pulley 16. Between the frames 10 and 11 the shaft 15 has mounted thereon and keyed thereto a revolute member 17 provided with a plurality of open-ended transverse chambers 18 extending to the periphery of said revolute member. 105

To the periphery of the revolute member 17 are secured a plurality of cutter blades 19 by means of bolts 20, one for each chamber 18, the cutting edges of said cutter blades extending slightly beyond the periphery of 110

said revoluble member. Each cutter blade 19 substantially closes the opening through the periphery of the revoluble member communicating with the transverse chambers 18, 5 there being just sufficient opening in advance of the cutting edge to permit the chips cut from the logs to pass into said chambers.

Each cutter blade 19 has cut therethrough from its rear edge a plurality of slots 21 of 10 greater depth at the bottom than at the top in each of which is mounted a knife 22, the cutting edge 23 of which extends beyond the periphery of the revoluble member a distance slightly in excess of the distance the 15 cutting edge 24 of the cutter blade is beyond said periphery. The slots 21 are equally spaced from each other and the cutting edges of the knives secured therein are at right angles to the cutting edge of the blade 19.

20 It is obvious from an inspection of the drawings that when the knives 22 are inserted in the slots 21 and the cutter blade 19 is secured by means of screws or bolts 20 to the revoluble member 17, said knives 22 are locked in position and cannot be accidentally displaced. Secured to the upper part of the frame 10 and 11 is a hopper 25 the upper and lower ends of which are open. The walls 26 of said hopper parallel to the 25 shaft 15 incline upwardly toward each other, the purpose of these inclined walls being to resist any tendency of the cutter blades 19 from forcing upwardly the logs contained therein and being cut by the various cutters 30 and knives secured to the revoluble member as said member revolves in the direction of the arrow "a" on Fig. 2 of the drawings.

A removable curved plate 27 is secured to the hopper 25 and the end frame 13. When 40 it is desired to remove the cutter blades 19 or the knives 22, access to the revoluble member may be secured by removing this cover 27. As the member 17 revolves in the direction of the arrow "a" the cutting edge 24 45 will shave from the under surface of the logs resting on the periphery of the member 17 portions of the surface thereof which portions will pass through the narrow opening 28 in advance of the blade 19 and into the 50 chamber 18. As soon as the blade 19 passes from beneath a log and has chipped therefrom a certain portion of its surface the log by the weight of those above will be forced downwardly and as the member 17 55 continues to revolve the knives 22 will come into contact with the outer surface of the logs and cut transverse incisions therein, the next blade 19 cutting from this surface chips of equal length, these chips entering the 60 chambers 18 as stated.

Opposite one end of the revoluble member 17 is a bonnet 29 which communicates by means of the pipe 30 with a suction fan or blower 31 driven by means of the pulley 32 65 and having an outlet 33, said blower being of

any well-known construction. During the operation of chipping the pulp wood the blower is driven at a high rate of speed sufficient to produce a suction that will draw from the chambers 18 the chips as fast as 70 they are cut from the surface of the logs. As the chips pass through the blower they are forced through the outlet 33 into a digester where they are treated in the usual manner.

75 It has been found in practice that by cutting chips from the logs with the grain running lengthwise of said chips, pulp is produced from which a superior quality of 80 the chips when reduced to a pulp having a binding effect on the paper manufactured from the pulp which makes it very tough and durable.

It is believed the operation and many 85 advantages of the invention will be fully understood from the foregoing.

Having thus described my invention, I claim:

1. In a machine of the class described, the 90 combination of an open-ended hopper; a revoluble member beneath said hopper having a plurality of transverse chambers extending therethrough from end to end and to its periphery; a peripheral cutter blade 95 extending transversely of said member at the mouth of each chamber; and a suction member operable independently of said revoluble member communicating with one end of said chambers whereby the chips cut 100 from the material are drawn into said chambers and from one end thereof into a delivery tube.

2. In a machine of the class described, the 105 combination of an open-ended hopper; a revoluble member beneath said hopper having a plurality of transverse chambers extending from end to end thereof and to its periphery; a peripheral cutter blade extending transversely of said member at the 110 mouth of each chamber and having a plurality of slots extending inwardly from its rear face; a knife in each slot the cutting edge of which extends beyond the periphery of said cutter blade with its edge at right angles thereto; and a suction device communicating with one end of said chambers.

3. In a machine of the class described, the 120 combination of an open-ended hopper; a revoluble member beneath said hopper having a plurality of transverse chambers extending to its periphery; a peripheral cutter blade extending transversely of said member at the mouth of each chamber and having a plurality of slots extending inwardly from 125 its rear face, said slots being deeper at the bottom than at the top; a knife in each slot the body portion of which fits said slot while its cutting edge extends beyond the periphery of said member and at right angles to 130

said cutter blade; and a suction device communicating with one end of said chambers.

4. In a machine of the class described, the combination of an open-ended hopper; a revolute member beneath said hopper having a plurality of transverse chambers extending to its periphery; a peripheral cutter blade extending transversely of said member at the mouth of each chamber, the cutting edge of which extends slightly beyond the periphery of said member; a plurality of knives, the cutting edges of which are at

right angles to and extend slightly beyond the cutting edges of said cutter blades; and a suction member communicating with one end of said chambers, whereby the chips cut by said blades and knives are drawn through said transverse chambers. 15

Signed by me at 4 Post Office Sq., Boston, Mass., this 2d day of April, 1910.

NATHANIEL LOMBARD.
